UNITED STATES PATENT OFFICE.

CARL HERMAN CLAUSEN, OF SOLVESBORG, SWEDEN, ASSIGNOR TO PATENTAKTIE-BOLAGET CENTRALSMÖRJNING, OF SOLVESBORG, SWEDEN, A CORPORATION OF SWEDEN.

FORCED-LUBRICATION APPARATUS.

Application filed May 11, 1927, Serial No. 190,626, and in Sweden May 19, 1926.

This invention relates to forced lubrication apparatus of the kind in which a single controlling or valve member for a number of pump pistons is arranged in central position between the pumps which are placed in annular relationship co-axially around the common valve member. Apparatus of this kind have previously been provided with a valve member with solely rotating motion 5 and provided with a cam disc for driving the pump pistons. In another earlier type there has been arranged centrally between the annularly disposed pumps a common driving member which has been subjected 10 to a reciprocating motion and at the same time an oscillatory motion, the said driving member being connected with the pump pistons by means of cranks, so that also the pistons have been subjected not only to a 15 reciprocating motion but also to an oscillatory motion, whereby they themselves have acted as valves.

The forced lubrication apparatus forming the subject matter for the invention is so to 20 say a compromise between the two above described types and comprises a central member which partly serves as valve member or valve piston in the real sense of the word and partly is subjected to two motions, 25 namely, a reciprocating motion which by suitable means is transferred to the pump pistons, and an oscillatory motion so as to be able to act as valve.

With this lubrication apparatus according 30 to the invention many advantages are obtained over older apparatus of a similar kind, and amongst these advantages are to be mentioned:—

(a) In comparison with the known type 35 having a valve member with solely rotating movements the advantage is gained that the valve member according to the invention may be subjected to its oscillatory motions during the intermediate periods between its 40 reciprocating movements and vice versa, so that the suction and pressure channels will be fully opened during the whole stroke of the pump pistons. For this reason the said channels may be constructed with smaller 45 dimensions than in an apparatus having a continuously rotating valve member and therefore the surface of tightness, given the same dimensions for the valve members, will be proportionally greater, or if only the 50 same surface of tightness is required the

dimensions of the valve member may be made proportionally smaller, which naturally affects the overall dimensions of the whole apparatus, and which is of the greatest importance, as the chief object is to obtain, very small apparatus with a great 60 number of pumps. In addition the pump pistons are driven according to the invention directly by the valve member by means of a simple carrier disc, and therefore the cam disc hitherto used has become superfluous, so that the pumps can be placed closer together 65 and the number of pumps be increased.

(b) In comparison with the known type 70 in which the pump pistons are moved up and down and at the same time oscillated to and fro the present apparatus shows the advantage that the connection between the central driving member and the pump pistons is considerably simpler, and the pump pistons 75 need not perform an oscillatory movement, because they are not adapted to serve themselves as valves. Also in this case the conditions with respect to tightness are much more advantageous, because the relatively 80 small pump pistons according to the invention have only to perform their pump action, while in the older type the pump pistons can only receive a very inconsiderable oscillatory motion and therefore the conditions 85 with respect to tightness at the pressure and suction openings are very unsatisfactory. It is further to be noted that in the older type the manner of transferring motion from the central driving member to the pump pistons 90 requires with necessity a greater space between the pumps and therefore greater overall dimensions of the whole apparatus.

The apparatus according to the invention 95 may be easily adjusted in a known manner, so that the various pumps may be set so as to supply different quantities of lubricating oil, but in addition the invention offers the advantage over the prior art that the apparatus may be taken to pieces with great 100 105 110 115 120 125 130 135 140 145 150 155 160 165 170 175 180 185 190 195 200 205 210 215 lubrication apparatus on the line *a*—*b*, Fig. 2. Fig. 2 is a top view of the same.

Fig. 3 is a vertical section of the apparatus on the line *c*—*d*, Fig. 2.

5 Fig. 4 is a horizontal section of the apparatus on the line *e*—*f*, Fig. 1.

Fig. 5 is a horizontal section of the apparatus on the line *g*—*h*, Fig. 1.

The characteristic feature of the invention 10 consists in that the operating member arranged in the centre of the pumps which are placed co-axially around the said member is subjected by means of suitable mechanisms not only to an oscillatory motion (instead of to a continuously rotating one) but also to a reciprocating motion, so that the said central member can by means of a simple carrier device directly transfer a similar reciprocating motion to the pump pistons 15 which however are not subjected to a rotary motion nor themselves need act as valve members.

Referring to the drawings the apparatus 20 consists of a main structure 1 with a central bore in which to receive a valve piston 2, and co-axially around the said piston, with a number of pumps having pump pistons 3. The central valve piston 2 extends entirely throughout the central bore and beyond the 25 same and is connected at its projecting lower end to a suitable driving mechanism to be described later on, and at its upper projecting end with a carrier device for the pump pistons 3.

30 The arrangement for subjecting the valve piston to the oscillatory and reciprocating motions consists in a manner known per se of a shaft 4 (Fig. 1) positioned substantially vertically in relation to the longitudinal axis of the valve piston and subjected to a continuously rotary or intermittently rotary motion, for instance, by means of a roller friction device 5 which is actuated by a lever 6. The shaft 4 is provided at its one 35 end with a preferably ball shaped crank pin 7 which, also in a manner known per se, projects into and engages with a recess 8 in a head 9 attached to the lower end of the central valve piston. It is to be understood 40 that the recess is substantially of the same width as the diameter of the ball shaped crank pin 7, while in vertical direction it is considerably longer than the said diameter, which results in that the valve piston will 45 have periodical dead motions at the ends of its reciprocating movements but no dead motion with respect to its oscillatory movements. This provision has been made so as to reduce the reciprocating movement of the 50 piston, when it oscillates, or with other words to limit the reciprocations to certain angles of the rotation of the crank pin and the oscillatory movements to other angles thereof.

55 To the upper end of the central valve pis-

ton 2 is attached a plane and circular flange or the like, for instance a removable disc 10 which is fastened to the said piston in a suitable way such as illustrated in the drawing. Also each of the pump pistons 3 is provided 70 with a similar but smaller flange 11 and further with adjustable stop members which may have the form of nuts 12, and the disc 10 is positioned with its edge between the flanges 11 and the nuts 12. By this means 75 the valve piston 2 obviously will transfer its reciprocating movements to the pump pistons 3 by means of the disc 10, and this independently of its rotary movements, and further the strokes of the pump pistons may 80 be varied by adjusting the position of the nuts 12 in relation to the flanges 11. As each pump piston has its own adjusting device each pump may be adapted individually to supply various quantities of lubricating oil to the places of utilization, all 85 in accordance with the requirements. In the position of the nuts as illustrated in the drawings the pump pistons will not be actuated and by screwing the nuts down nearer to the flange 11 the distance between the lower nut and the flange 11 will be reduced and thus the disc 10 may in its reciprocating movements move the pump piston.

90 A common oil inlet for all pumps is arranged at the upper part of the main structure 1 and consists of a socket 13 which is in communication with an inner chamber 14 which is formed by turning down a portion 95 of the valve piston. The recess thus formed in the valve piston has such length that the inlet is never covered by the piston. Each pump has its separate discharge socket 15 and in order that the various sockets shall 100 not be in the way for one another they are attached to the structure alternately at different levels, as shown in Figs. 1 and 3, the socket on the line *a*—*b* (Fig. 2), for instance, being at a higher level than the sockets on the line *c*—*d*. In the example shown three 105 sockets are in one and the same higher level and four sockets in one and the same lower level.

110 In spite of these different levels for the outlets the pump pistons have all the same length, and therefore they are interchangeable. It is however to be understood that the pump pistons and their respective cylinders should be marked, in case the pumps are 115 adjusted, by means of the nuts 12, to deliver different quantities of lubricating oil to the various places of utilization, so that the piston pumps, when the apparatus is taken to pieces and re-assembled again, are 120 placed in their proper cylinders.

125 At the upper portion of the valve piston 2 are provided grooves 16 which are in communication permanently with the chamber 14 and which serve as suction channels for the pumps having their outlets arranged at 130

a higher level. Similar grooves 17 are arranged at a lower portion of the valve piston 2 for the pumps having their outlets at a lower level, and these grooves 17 are in communication by means of radial channels (as shown in Figs. 1 and 3) with a central bore 18 in the valve piston, which is connected with the chamber 14 by radial channels 19. The lubricating oil in the reservoir, 10 not shown, therefore has always free access to the grooves 16, 17, and when the valve piston during its oscillatory movements is in a certain angular position the grooves will register with the suction channels 20 leading to the pump cylinders either directly for the pumps having their outlets at a higher level or by means of connecting channels 21 for the pumps having their outlets at a lower level (Figs. 3 and 5). 15

For the last named pumps the valve piston is further provided with grooves 23 serving as pressure channels and similar grooves 22 are provided on the valve piston for the first named pumps. These grooves 25 22 and 23 are adapted to connect at a certain angular position of the valve piston the pump channels 20 with the outlets 15. This will make it clear that the oscillatory movements of the valve piston 2 will comprise 30 an angle which is as great as the angular distance between a suction channel 16 or 17 and the corresponding pressure channel 22 or 23. Although this kind of valve regulation is known in the art the invention 35 differs from the conventional design in that the grooves on the valve piston are placed alternately at different levels, so that the relative reduction in overall dimensions of the valve piston, as intimated above, is rendered possible. 40

The pump pistons may easily be taken out and inserted again after removal of the protecting hood 24 and unscrewing the bolt which fixes the disc 10 to the valve piston 2.

To remove the valve piston 2 the shaft 4 is journalled in a separate casing 25 attached to the main structure 1, the casing having a chamber 26 surrounding the driving mechanism 7, 8, 9. Access to the chamber 26 is obtained by unscrewing a screw stopper 27 (Fig. 1). The casing 25 is fastened to the main structure 1 by means of screws 28, the main structure being provided with a guide collar 29. When it is desired 50 to take out the valve piston, the screws 28 are unscrewed and either the main structure 1 is lifted up or the casing 25 is drawn down, whereby the valve piston is drawn out of the central bore, and after the collar 55 29 has left the upper edge of the casing 25, the main parts may be moved laterally in relation to each other so that the ball shaped crank pin 7 can leave the recess 8, whereupon the main parts can be wholly separated 60 and the valve piston drawn out.

When the apparatus is re-assembled it is impossible to place the valve piston in a wrong position, because it can be connected to the crank pin 7 in one manner only, and therefore the apparatus is fool-proof also in 70 this respect. Also the outlet sockets 15 are of one and the same design and therefore interchangeable.

The apparatus as a whole may of course be combined with or placed directly on an 75 oil reservoir but it is chiefly designed to enable the apparatus to be mounted at any desired place and the oil reservoir at another place.

In certain applications of the lubricating 80 apparatus, for instance in the lubrication of automobiles in which the crank case is provided with a larger lubricating oil reservoir from which the oil is pumped to certain places requiring lubrication and returns 85 therewith to the reservoir in continuous circulation, while other places of lubrication—for instance the engine cylinders—always require fresh oil, it appears preferably to combine the lubricating apparatus according 90 to the invention with an additional pump device, and this of a greater capacity than the apparatus. To this end the head 9 on the valve piston 2 may be extended, as shown with dash-dotted lines in Fig. 3, by a piston 95 rod connected to a piston 30 which reciprocates in a cylinder 31 provided with suitable inlets and outlets. Obviously the piston 30 will receive in the same manner as the valve piston 2 both a reciprocating 100 and an oscillatory motion, and the latter motion may be utilized for the piston 30 to serve simultaneously as valve in order to produce a valveless pump of known kind. In such a case the pump 30, 31 may be employed for the circulation of great oil quantities and should therefore be designed with correspondingly greater dimensions, while the pumps 3 are adapted to supply fresh oil 105 to the places requiring such renewed lubrications. 110

The details above described have no deciding influence upon the invention in another degree than what the function of the said details requires, and therefore they may be modified or replaced by equivalent means without departing from the main spirit of the invention. For this reason the invention is not limited to the details which have been described in the foregoing description 115 for explicating the invention. 120

What I claim and desire to secure by Letters Patent is:—

1. A forced lubrication apparatus, comprising a main structure of substantially cylindrical form, a single central valve member, a number of pumps having reciprocating pistons arranged in annular relationship coaxially in relation to the central valve member, operative means for subjecting the cen- 125 130

tral valve member partly to reciprocating motions and partly to oscillating motions, and means for transferring the reciprocating movements of the central valve member to the pump pistons.

2. A forced lubrication apparatus, comprising a cylindrical main structure having a central bore to receive a piston like valve member which extends with both its ends beyond the main structure, the lower projecting end of the valve member in engagement with operative means for subjecting the valve member to reciprocating and oscillating motions, a number of pumps having pistons arranged in annular relationship co-axially in relation to the valve member, and the upper projecting end of the valve member provided with carrier means in engagement with the pump pistons.
3. In a forced lubrication apparatus of the kind as claimed in claim 2, the carrier means constituted by a circular disc attached to the upper projecting end of the central valve member, the pump pistons provided with stop and carrier means arranged in the path of the said circular disc, so that the pump pistons will be reciprocated in accordance with the reciprocations of the valve member, while the oscillating movements of the valve member are not transferred to the pump pistons.

4. A forced lubrication apparatus comprising a cylindrical main structure having a central bore to receive a piston-like valve member which extends with both its ends beyond the main structure, means engaging the lower projecting ends of the valve member for subjecting such valve member to reciprocating and oscillating motions, a plurality of pumps having pistons arranged in annular relationship coaxially with the valve member, a circular disk attached to the upper projecting end of the valve member, and stop and carrier means connected with the pump pistons in the path of movement of the circular disk, said stop and carrier means being relatively adjustable in the direction of travel of the pistons for varying the length of stroke of the latter in the movement of the valve member.

5. In a forced lubrication apparatus of the kind as claimed in claim 1, the operative means consisting of a driven shaft jour-

nalled substantially at right angles to the axis of the central valve member and provided at its one end with a ball shaped crank pin in engagement with a recess in the central valve member, the recess having substantially the same width as the diameter of the ball shaped crank pin but a greater length in vertical direction than the said diameter.

6. A forced lubrication apparatus, comprising a cylindrical main structure, a piston like valve member arranged centrally within the main structure the valve member projecting at both its ends beyond the main structure, a number of pumps having pistons arranged in annular relationship co-axially in relation to the central valve member, the upper projecting end of the valve member provided with carrier means in engagement with the pump pistons, a separate structure detachably attached to the lower end of the main structure and provided with operative means in engagement with the central valve member for subjecting the latter to reciprocating and oscillating motions.

7. A forced lubrication apparatus, comprising a cylindrical main structure, a piston like valve member arranged centrally within the main structure, a number of pumps having pistons arranged in annular relationship co-axially in relation to the central valve member, operative means for subjecting the valve member to reciprocating and oscillating motions, carrier means on the valve member and in engagement with the pump pistons for subjecting the latter to reciprocating motions only, a common inlet for all pumps, separate outlets for each pump, the inlet in communication with the various pumps by means of suction channel means on the valve member and the outlets in communication with the various pumps by means of pressure channel means on the valve member.

8. In a forced lubrication apparatus of the kind as claimed in claim 7, in which the outlets for the various pumps arranged at the same level are alternately at different levels on the main structure.

In testimony whereof, I have signed my name to this specification.

CARL HERMAN CLAUSEN.
